UNITED STATES PATENT OFFICE.

BYRON G. BAKER, OF LAPORTE, INDIANA, ASSIGNOR TO M. RUMELY COMPANY, OF LAPORTE, INDIANA, A CORPORATION OF INDIANA.

CARBURETER.

1,142,793.

Specification of Letters Patent. Patented June 15, 1915.

Application filed September 8, 1913. Serial No. 788,518.

To all whom it may concern:

Be it known that I, BYRON G. BAKER, a citizen of the United States, residing at Laporte, in the county of Laporte and State 5 of Indiana, have invented a certain new and useful Improvement in Carbureters, of which the following is a specification.

In the use of engines of the internal combustion type designed to burn kerosene and 10 the heavier fuel oils, the starting problem is always one of extreme difficulty. Customarily the engines are primed with gasoline and when the gasoline is used up the operator turns on the kerosene. It is very 15 important that he turn on the kerosene at the precisely correct moment because if he fails to do this, there is a possibility of one or two strokes being made without fuel, and the temperature of the engine will instantly 20 drop down to such a point that the kerosene may not burn, or else there is a possibility that if the kerosene is turned on too soon the engine may be badly carbonized by the burning rather than the exploding of the excess 25 kerosene in the cylinder. It is necessary then to go back and start again on gasoline, and it is, therefore, highly desirable to have some absolutely accurate and reliable automatic means quite independent of the operator 30 for turning on the kerosene when the gasoline has been used up and not before.

I propose, therefore, to provide means responsive only to the consumption of the fixed, predetermined and adequate supply of 35 gasoline for turning on the kerosene.

I have not illustrated my device as applied to a water supply, but it will be obvious that it might so be applied, and under some circumstances, this would be done. 40 There are obviously a number of ways of producing the result which I have aimed at. The device which I have described satisfactorily produces this result, but many other devices would probably do so depending all 45 together on the circumstances of the case.

Thus my invention relates to improvements in carbureters and has for one object to provide means for supplying a priming fluid to a carbureter adapted to burn a 50 heavier type of fuel, and to subsequently at the proper instant turn on the regular or normal heavy fuel supply. It is illustrated diagrammatically in one form in the accompanying drawings, wherein—

55 Figure 1 is a side elevation with parts

broken away and parts in section; Fig. 2 is an end elevation looking toward the right hand side of Fig. 1 with parts in section and parts broken away; and Fig. 3 is a section along the line 3—3 of Fig. 1.

Like parts are indicated by like letters in all of the figures.

A is a carbureter casing or housing containing a vacuum mixing or carbureting chamber A¹ and a water reservoir A² and 60 the liquid fuel reservoir A³. Needle valves A⁴ controlled and adjusted by thumb screws A⁵ lead respectively from the fuel and from the liquid reservoirs and discharge into the carbureting chamber.

B is a mixture discharge manifold communicating with the engine cylinders through pipes B¹.

B² is a mixture discharge port interposed between the carbureting chamber and the 75 manifold.

B³ is a piston valve controlling said port.

B⁴ is a valve stem slidably mounted and guided in and by the sleeve B⁵ and controlling the piston valve B³.

B⁶ is a valve lever pivoted to the valve stem B⁴ and actuated and operated by any suitable means to control the piston valve and thus the discharge of mixture from the carbureter.

C is an air intake passage leading to air intake port C¹ in the wall of the carbureting chamber.

C² is a valve cage surrounding the end of the intake passage.

C³ is a thimble or cage valve weighted and free to slide up and down within the cage C².

C⁴ and C⁵ are ports or slots respectively in the valve and cage, which are adapted to be brought into register one with the other and 95 permit air to enter the mixing chamber when the vacuum therein is sufficient to cause the air pressure on the lower side of curved top of the thimble to lift the valve against the weight of gravity.

C⁶ is a guide pin upon which is slidably mounted the sleeve C⁷. It supports and guides the valve.

C⁸ is a butterfly valve in the end of the air passage C by manipulating which it may be 105 closed.

D is an auxiliary air passage downwardly depending from the air intake passages C and communicating therewith at a point immediately below the cage or intake valve.

- D¹ is a funnel shaped flange surrounding and projecting from the lower edge of the passage D.
- D² is a cup-shaped fuel reservoir designed to contain the priming liquid supported by means of the cap screws D³ from the flange D¹.
- D⁴ is a cover for the reservoir D² and is inwardly distorted or recessed at D⁵.
- D⁶ is a fixed fuel supply pipe supported in the cover D⁴ extending downwardly to substantially the bottom of the cup D² and terminating at its upper end in the supply or discharge nozzle D⁷.
- D⁸ is a downwardly extending truncated conical partition having a perforate cylindrical flange D⁹ about the periphery thereof adapted to be engaged and held between the cover D⁴ and the flange D¹.
- D¹⁰ is a funnel upwardly projecting supported in the truncated conical partition D⁸ and surrounding the fuel nozzle D⁷. It is in effect a Venturi tube into which the fuel nozzle may discharge.
- D¹¹ is a port through the cover D⁴ whereby air may enter the space between the cover D⁴ and the partition D⁸ and flange D¹ thence to pass up through the Venturi tube to discharge into the air intake passage D.
- E is a gasoline float located in the priming cup D² and surrounding the fuel pipe D⁶.
- E¹ is a lever rigidly attached to the float E and pivoted at its other end to the wall 35 of the cup D².
- E² is a plunger valve resting on the lever E¹ in opposition to the conical valve seat E³.
- E⁴ is a gasoline or priming fuel supply pipe leading from the priming fluid supply 40 not shown, and controlled by the valve E³ to and discharging into the priming cup.
- E⁵ is a valve lever pivoted on the priming cup D².
- E⁶ is a connecting rod leading from one 45 end of said lever to the plunger valve E² so that when the priming cup is full and the float is lifted as indicated in Fig. 3, the lever will be in a horizontal position.
- F is a valve housing mounted in the wall 50 of the priming cup D².
- F¹ is a kerosene or heavy fuel supply pipe leading from the supply not shown and controlled by the engine pump not shown to the valve housing F.
- F² is a discharge pipe leading from the valve housing F back to the reservoir which 55 supplies the heavy fuel in the pipe F¹.
- F³ is a valve in the pipe F² connected by means of the rod F⁴ with the lever E⁵ and 60 normally pressed shut by the spring F⁵ but held as indicated in Fig. 2 open by the downward pressure of the rod F⁴, caused by the downward pressure of the rod E⁶ in response to the buoyancy of the float.
- F⁶ is a pipe leading from the valve hous- 65
- ing between the valve F³ and the pipe F¹ to the fuel supply chamber, so that when the valve F³ is closed fluid will be pumped to the chamber, but when the valve F³ is open the fluid will return to the main supply reservoir without being pumped into the chamber.
- H⁶ and F⁸ are water supply and overflow pipes whereby the water reservoir may by any suitable means as indicated be kept supplied with liquid.
- It will be evident that, while I have shown in my drawings an operative device and one which would under many circumstances be perfectly satisfactory, still it is unquestionable that the same result might be obtained by other means, and I, of course, wish, therefore, to have my drawings and specification construed as being to a large degree diagrammatic and merely illustrative of what for the present, at least, is a preferred form adapted to effect the desirable result.
- H is a shaft upon which is mounted the arm E⁵ and also the rock arm H¹. This rock arm H¹ carries a stem H² which supports the puppet valve H³ in the valve chamber H⁴.
- H⁵ is a water supply pipe leading from a suitable source not here shown.
- H⁶ is a pipe leading from the valve housing H⁷ to the carburetor water chamber as indicated.
- H⁸ is a discharge pipe controlled by the puppet valve H³.
- H⁹ is a spring tending normally to hold the puppet valve H³ closed. When the shaft H is rocked by the liquid in the receptacle D² raising the float E, it presses down the puppet valve H³ against the spring H⁹ and permits the water to flow out through the pipe H⁴. When the reservoir D² is empty, the spring closes the valve and the water comes on up through the pipe H⁶ to the carburetor.
- The use and operation of my invention are as follows: In starting an engine equipped with my carburetor gasoline is forced by a hand pump not shown through a pipe in the usual manner into the gasoline reservoir until the proper starting level has been reached. This may be told by inspection of the gasoline reservoir or by the feel of the pump or by any other suitable and satisfactory manner. It will be noted that the pipe leading from the hand pump not shown to the gasoline reservoir is closed by the plunger valve and when the reservoir is filled the plunger valve is pushed up to close the opening, owing to the buoyancy of the float. This will resist the movement of liquid in the pipe toward the reservoir but, of course, not completely stop it. The resistance, however, will be sufficient to enable the operator to tell by the pressure he is exerting whether or not the reservoir is full.

The presence of the body of gasolene in the reservoir raises the float and this float operates the plunger or connection to work the lever which operates the valve so that the liquid which is pumped from the storage kerosene reservoir not here shown is returned directly thereto instead of being pumped to the kerosene supply chamber in the carbureter. Any form of valve might be used but I prefer to use a valve which merely closes the return pipe to the main kerosene or heavy fuel reservoir. When this valve is closed the liquid cannot return directly to the reservoir but is forced up to the carbureter and fills the fuel supply in the carbureter itself. The butterfly valve in the air intake pipe will then be closed and the engine started in the usual manner drawing its firing charge from the gasolene priming carbureter. The air will enter into or through the gasolene chamber and pass up through the Venturi tube around the gasolene nozzle and the gasolene will then be drawn out by the air to form a combustible charge. This combustible charge of vaporized gasolene and air will be drawn up through the weighted intake valve into the kerosene carbureter and thence be discharged into the manifold to operate the engine. The engine will then run on gasolene for a time. However, as no further gasolene will be supplied to the float chamber the gasolene level will commence to fall. The float will sink also, and the kerosene valve will be gradually operated to force a gradually increasing supply of kerosene to the carbureter reservoir, the kerosene carbureter receptacle will soon be completely filled and a limited surplus of kerosene will be free to enter the carbureting chamber and become there mixed with the inpassing air. Meanwhile, however, since the level of the gasolene will have been constantly reduced, the height to which the gasolene must be raised above the reservoir level to discharge at the nozzle will be increased and a gradually diminishing amount of gasolene will be fed to the carbureter, owing to the increased resistance of the lengthened column of liquid to be raised. Thus the mixture will gradually change from straight gasolene to part gasolene and part kerosene and then as the gasolene is completely used up the kerosene supply will be wide open and the engine will run on kerosene alone, since by this time the engine will have been heated up to such a point that kerosene can satisfactorily be consumed. The operator can at any time then open the butterfly valve and permit cold air or if desired hot air from the exhaust manifold not here shown to enter the carbureting chamber. If, however, he neglects to do this, air will continue to enter the carbureting chamber through the priming carbureter and no particular

harm will be done except that possibly the power of the engine will be slightly reduced owing to the slightly increased drag of the air being fed thereto. It will be noted that it makes no difference through which of the two openings the air enters the carbureter, since the air passing through either will have to enter the carbureter through the balanced or weighted intake valve in the intake port.

No adjustments have been provided or are needed for the gasolene nozzle and reservoir. The size of the Venturi tube and nozzle will be selected when the engine is designed and put in place and no further changes or adjustments are required because gasolene is such an easily carbureted and burned liquid that all that is needed is to mix it some way with the air and get it some way into the cylinder, and an excess of gasolene can do no particular harm, and it is needful, therefore, to design the parts only so that the gasolene at the beginning of the operation is sufficient or in excess and the machine will take care of itself.

It will be noted that the same controlling mechanism which controls the kerosene simultaneously operates to control the water so that when the engine is being started up no water can possibly be fed to the carbureting chamber, although this is not so important because the engine will at first on no load or low load normally take a very limited supply of water if any so that under the starting conditions no water would probably be fed even if my device were not applied to it.

I have used the term kerosene but it must be understood that I use it merely because kerosene is that fuel which most frequently will be used in my device but I am using the term only as a general term applicable to the general types of heavier fuel liquids. Engines are operating with my carbureter using a number of other liquid fuels, some even using the crude oils that come from the wells, so kerosene must not be definitely limited to that fraction known to the refining art as kerosene.

Thus in actual practice I have a system which would need six reservoirs, three storage reservoirs and three carbureter reservoirs, a storage reservoir for the priming fluid from which it may be pumped from the priming cup or priming fluid reservoir by the hand of the operator or otherwise only at certain needed intervals when the engine is to be started and a storage reservoir for the kerosene or heavy fuel from which it will be pumped by an engine driven pump in a constantly flowing stream either to be returned directly back to the storage reservoir when the float actuated valve is opened or else to be pumped to the liquid receptacle in the carbureter whence the overflow might

still return to the storage reservoir, this occurring when the float actuated valve is closed, and a water reservoir system whose operation is substantially similar to the kerosene storage system.

I claim:

1. In a carbureter for heavy fuels means for supplying a fixed amount of priming fluid and means responsive to the consumption of the priming fluid for turning on the heavy fuel.
2. In a carbureter for heavy fuels means for supplying a fixed amount of priming fluid and means responsive to the gradual consumption of the priming fluid for gradually turning on the heavier fuel.
3. In a carbureter for heavy fuels and water means for supplying a fixed amount of priming fluid and means responsive to the consumption of the priming fluid for turning on the heavier fuel and the water.
4. In a carbureter for heavy fuels and water means for supplying a fixed amount of priming fluid and means responsive to the gradual consumption of the priming fluid for gradually turning on the heavy fuel and the water.
5. In a carbureter having a plurality of fuel reservoirs means responsive to the lowering of the level in one of them for supplying fuel to the other.
6. In a carbureter having a plurality of fuel reservoirs means responsive to the gradual lowering of the level in one of them for gradually turning on the fuel supply to the other.
7. A carbureter comprising a carbureting chamber and a fuel reservoir, means for supplying a priming fluid to the air before it enters the carbureting chamber and means responsive to the gradual consumption of said priming fluid for gradually supplying fuel to the fuel reservoir.
8. A carbureter comprising a carbureting chamber and fuel and water reservoirs, means for supplying a priming fluid to the air before it enters the carbureting chamber and means responsive to the gradual consumption of said priming fluid for

gradually supplying liquid to said reservoirs.

9. In a carbureter for heavy fuels the combination of means for first supplying a priming fluid to the carbureter, means for supplying a heavy fuel to the carbureter and means for simultaneously diminishing the flow of the priming fluid and increasing the flow of the heavy fuel automatically.

10. In a carbureter for heavy fuels the combination of means for first supplying a priming fluid to the carbureter, means for supplying a heavy fuel to the carbureter and means for simultaneously diminishing the flow of the priming fluid and increasing the flow of the heavy fuel automatically, said last mentioned means responsive to variations in the supply of the priming fluid.

11. In a carbureter for heavy fuels the combination of means for first supplying a priming fluid to the carbureter and means for subsequently supplying a heavy fuel to the carbureter and controlling means for said heavy fuel, said means responsive to variations in the amount of priming fluid.

12. A carbureter comprising a carbureting chamber, air intake and mixture discharge ports, means for supplying a normal, running fuel to said carbureting chamber and means for supplying a priming fuel to the air entering said carbureting chamber before it enters the intake port and means responsive to said priming fuel supply means for controlling the supply of normal, running fuel.

13. In a carbureter a priming cup, a float therein, a normal, running fuel supply and controlling means therefor, said controlling means operative responsive to the position of the float in the priming cup.

In testimony whereof, I affix my signature in the presence of two witnesses this 26th day of August, 1913.

BYRON G. BAKER.
